(57) **CLAIM**

The ornamental design for an infusion pump, as shown and described.

DESCRIPTION

FIG. 1 is a perspective view showing a new design for an infusion pump;

FIG. 2 is a front view of FIG. 1;

FIG. 3 is a rear view of FIG. 1;

FIG. 4 is a right-side view of FIG. 1;

FIG. 5 is a left-side view of FIG. 1;

FIG. 6 is a top view of FIG. 1;

FIG. 7 is a bottom view of FIG. 1;

FIG. 8 is a perspective view of the infusion pump of FIG. 1 with its head removed;

FIG. 9 is a front view of FIG. 8;

FIG. 10 is a rear view of FIG. 8;

FIG. 11 is a right-side view of FIG. 8;

FIG. 12 is a left-side view of FIG. 8;

FIG. 13 is a top view of FIG. 8;

FIG. 14 is a bottom view of FIG. 8;

FIG. 15 is a perspective view of the infusion pump of FIG. 1 shown in the context of being connected to infusion lines;

FIG. 16 is a front view of FIG. 15;

FIG. 17 is a rear view of FIG. 15;

FIG. 18 is a right-side view of FIG. 15;

FIG. 19 is a left-side view of FIG. 15;

FIG. 20 is a top view of FIG. 15; and,

FIG. 21 is a bottom view of FIG. 15.

The broken line areas of the infusion pump are included for the purpose of illustrating environment and form no part of the claimed design.

1 Claim, 13 Drawing Sheets
